CENTRALIZED TRAFFIC CONTROLLING
SYSTEM FOR RAILROADSNeil D. Preston, Rochester, N. Y., assignor to
General Railway Signal Company, Rochester,
N. Y.

Application May 16, 1936, Serial No. 80,096

19 Claims.

(Cl. 246—3)

This invention relates to centralized traffic controlling systems for railroads and it more particularly pertains to a system of the non-coded or direct control type as distinguished from a selector type system.

This invention is to be considered an improvement over the prior application Ser. No. 741,626, filed August 27, 1934, by T. J. Judge, and no claim is made in this application to subject matter common with such prior application.

In accordance with the present invention it is proposed to provide means for controlling a remote power operated track switch by applying energy of selected polarity to a first line circuit at the control office and to govern the movement of traffic over this switch by applying energy of selected polarity to a second line circuit at the control office.

It is also proposed to transmit signal indications from the remote location to the control office by applying energy of selected polarity to the first line circuit at the remote location and to transmit OS indications from the remote location to the control office by applying energy of selected polarity to the second line circuit at the remote location.

Furthermore, switch indications are transmitted from the remote location to the control office by applying energy of selected polarity to a third line circuit at the remote location. Approach indications for two approach track sections are also transmitted over the third line circuit by applying energy of selected polarity to this line circuit at the remote location.

These three line circuits are conveniently referred to in the following description as the W line, the X line and the Y line, with the C line forming the common return for the other three lines.

It is further proposed to provide such interlocking of the circuits in the communication of controls and indications that the transmission of conflicting controls is prevented, with the system retaining sufficient operating flexibility to permit efficient governing of traffic movements.

Other objects, purposes and characteristic features of the present invention will appear as the description progresses, during which reference will be made to the accompanying drawings which illustrate in a diagrammatic and conventional manner one specific embodiment of the present invention, the arrangement of which may be modified in practice depending on the type of control required, the character of and the number

of indications desired in the particular application.

In the accompanying drawings a complete communicating system is shown for transmitting controls and indications between a typical outlying field station (illustrated in Fig. 2) and the associated central control office (illustrated in Fig. 1). It will be understood that, in an actual installation of this system, separate control circuits are required for each station, these circuits comprising a duplicate of the W, X, and Y lines illustrated in the present drawings, with common wire C serving as the common return.

A mid-tap battery OB is provided in the control office and a mid-tap battery SB is provided at the field station, with the mid-taps of these batteries connected together by common wire C as illustrated in the lower portion of the drawings.

A track diagram is provided in the control office which corresponds to the associated typical track section at the field station, by means of which the operator is readily advised as to the position of the track switch, the condition of the associated signals, as well as the OS indications for the section of track with which the illustrated track switch is associated and two approach track sections.

The circuit arrangement in the control office is shown in Fig. 1 and the circuit arrangement at the associated field station is shown in Fig. 2.

Referring to Fig. 1, a signal control lever SGL is employed to set up the controls for the wayside signals which govern traffic over the illustrated track switch. This lever is operable to three positions, namely, west, stop and east as indicated by the reference letters W, S and E respectively. Suitable contacts are indicated as being closed when lever SGL is in either of its extreme operating positions, with these contacts being open when the lever is in its center or stop position.

A switch control lever SML is provided and operable to either of two positions for setting up controls for the associated switch machine at the field station, to position the track switch to either its normal or reverse position. The two positions to which lever SML can be operated are normal and reverse as indicated by reference letters N and R respectively. The contacts of the switch machine lever are preferably of the snap action type so that they will be rapidly switched from one position to the other irrespective of the speed of operation of the lever which controls these contacts.

The OS lamp associated with the track diagram is for the purpose of indicating to the operator

the occupied and unoccupied condition of the remote track section with which the illustrated track switch is associated. Approach lamps **1AT** and **2AT** associated with the illustrated track diagram are for the purpose of indicating the occupied and unoccupied condition of approach track sections **1A** and **2A** respectively.

Normal and reverse switch indicating lamps **NI** and **RI** indicate the track switch in its normal and reverse locked positions respectively by the illumination of the respective lamp. Neither lamp illuminated indicates that the associated track switch is either in its unlocked or mid-stroke position or that the switch is not in correspondence with the position of lever **SML**.

Signal indication lamps **ESK** and **WSK**, associated with the track diagram, indicate the conditions of the associated signals **ES** and **WS** (also **WSA**) respectively at the remote location. The illumination of lamp **ESK**, for example, indicates that signal **ES** is clear and the illumination of lamp **WSK** indicates that either signal **WS** or **WSA** is cleared.

Relay **GK** in the control office is the signal indicating relay which repeats the signal indications from the remote location in response to the control transmitted over **W** line. Relay **GZ** at the field station is the signal control relay which controls the field station signals in response to the control transmitted over **Y** line.

Relay **WK** in the control office is the switch position indicating relay which is operated in response to controls transmitted from the field station over **X** line. Relay **WZ** at the field station is the switch control relay which controls the associated switch machine in response to switch controls transmitted over **W** line.

Relays **1TK** and **2TK** are the approach indication relays which are operated in response to approach indications transmitted from the remote station over **X** line. Rectifiers **1R** and **2R** are for the purpose of transmitting the polarized current applied to **X** line to the proper **TK** relay. Relay **OSR** is the **OS** lamp signal relay which controls the **OS** lamp in response to the condition of **Y** line when signal lever **SGL** is actuated.

Relays **W** and **G** in the control office are transfer relays and are for the purpose of transferring the line circuits from one control to another as will be specifically pointed out later in the description. Relay **T** at the field station is the track relay associated with the track section with which the illustrated track switch is associated. Track relays **T¹** and **T²** are associated with approach track sections **1A** and **2A** respectively. Relays **EM** and **WM** are the signal indicating relays at the field station which are both energized as long as all illustrated signals are at stop. Although the control circuits for these relays are not shown it will be obvious that relay **EM** is de-energized when signal **ES** is cleared and relay **WM** is de-energized when either signal **WS** or **WSA** is cleared. Relay **TPX** is a relay which responds to the simultaneous occupancy of both approach track sections and is for the purpose of transmitting polar impulses over **X** line for the purpose of operating the proper **TK** relay (or relays) in accordance with the condition of the approach track sections.

Suitable wayside signals **ES**, **WS** and **WSA** are indicated in the conventional manner as being of the light signal type for governing traffic movements over the track switch **TS**. These signals are selectively cleared in accordance with the position of signal control relay **GZ** and in accordance

with the proper position of the track switch as repeated by the contacts of correspondence relay **WP**, these contacts being included in the signal circuits, but which are omitted from the present drawings, since this portion of the circuit arrangement forms no part of the present invention and is immaterial for an understanding thereof. Relay **WP** is the usual switch position repeating relay which, when energized, indicates that the associated track switch is in its locked condition and which indicates this switch in its normal and reverse positions by its polar contacts being positioned to the right and left respectively.

In tracing the circuits during the following description of the operation of the system, (+) and (-) will be considered opposite terminals of a local source of energy **OB** at the control office and also of a similar local source of energy **SB** at the field station.

It is believed that further description of the present invention will best be understood by considering the operation under certain characteristic or typical conditions.

Operation

In the accompanying drawings, track switch **TS** is shown in its normal position for routing traffic straight through on the main track in accordance with the normal position **N** of switch control lever **SML**. Normal switch indicating lamp **NI** is lighted to indicate that the switch is in correspondence with the switch machine lever. This energizing circuit for lamp **NI** extends from (+), contact **10** of lever **SML** in its normal position, lamp **NI**, contact **11** of relay **WK** in its right hand (normal) position, front contact **12** of relay **WK** and winding of relay **WK** to (C).

All of the signals associated with the illustrated track section are shown at stop as indicated by contact **100** of relay **GZ** being in its dropped away position. This is in accordance with the center or stop position of signal lever **SGL** in the control office and since front contact **13** of relay **GK** is open, lamps **ESK** and **WSK** are de-energized.

Normal conditions.—With the track sections at the field station unoccupied and with the control levers in the positions illustrated, the various devices, relays and circuits assume positions and conditions of energization as illustrated.

Track relays **T**, **T¹** and **T²** are normally energized in the usual manner because it is assumed that the associated track sections are unoccupied. With the switch machine in its normal locked position, relay **WP** is energized with current of a proper polarity for positioning its polar contacts to the right.

With all signals at stop, relays **EM** and **WM** are energized over circuits not shown. It will be understood that relays **WZ**, **WP**, **GK** and **WK** are of the polar neutral magnetic stick type, that is their neutral contacts assume dropped away positions when the windings of these relays are de-energized and assume picked up positions when their windings are energized. The polar contacts are assumed to be positioned to the right when current flows through the windings of the relays from left to right and positioned to the left when current flows through the windings of these relays from right to left. The polar contacts are maintained in the positions to which they are last actuated when the windings of the relays are de-energized.

Operation of track switch.—It will be assumed that the operator desires to reverse track switch **TS** in order to route traffic over the passing sid-

ing and for accomplishing this purpose lever SML is operated to its reverse position. The opening of contact 10 of lever SML puts out the normal indicating lamp NI and de-energizes relay WK. The de-energization of relay WK, following the actuation of the switch machine lever to its reverse position, closes a circuit for energizing W line with (—) energy which extends from (—), contact 14 of lever SML in its reverse dotted line position, back contact 15 of relay WK, winding of relay W, back contact 16 of relay G, W line conductor, back contact 116 of relay GZ, winding of relay WZ and front contact 115 of relay T to (C).
 5 This (—) energization of W line conductor picks up relay W in the control office and relay WZ at the field station, actuating its polar contacts to the left. At contact 101 of relay WZ, the normal control wire NC is de-energized and 10 the reverse control wire RC is energized for operating the switch machine to its reverse position.
 15

During this operation of the switch machine, lamps NI and RI are de-energized as an indication that the track switch is not in correspondence with the switch machine lever. When the track switch assumes its reverse locked condition, relay WP is again energized and its polar contacts are actuated to the left. A circuit is 20 now closed for energizing the X line with (+) energy which extends from (C), winding of relay WK, front contact 17 of relay W, X line conductor front contact 117 of relay WZ, front contact 118 of relay WP, contact 119 of relay WP 25 in its left hand dotted position and contact 120 of relay WZ in its left hand dotted position to (—).
 30

In response to this (+) energization of X line relay WK is energized and its polar contacts 35 are positioned to the left. A stick circuit for relay WK is now established which extends from (C), winding of relay WK, front contact 12 and contact 11 in its left dotted position, lamp RI and contact 18 of lever SML to (—). Since this 40 stick circuit includes lamp RI, this lamp is illuminated as an indication that the track switch at the remote location is in its reverse locked condition in correspondence with lever SML in the control office.
 45

50 The picking up of relay WK and the consequent opening of back contact 15 de-energizes W line and in response to this de-energization relays W and WZ are de-energized. The dropping of relay W in the control office de-energizes the X line conductor at open front contact 17 and relay WZ at the field station opens the X line conductor at front contact 117. Relay WK remains stuck up however over the above described stick circuit.
 55

60 It will be understood that suitable approach locking is provided in the control circuits for the switch machine SM, but in order to simplify the present disclosure, such locking means have been omitted from the drawings, since these circuits form no part of the present invention.
 65

The operation involved in operating the track switch from its reverse locked position to its normal locked position is merely the reverse of the operation already described and will not be 70 specifically pointed out. Such reverse operation may be understood by analogy, considering that lever SML, when returned to its normal position de-energizes the stick circuit for relay WK, after which W line conductor is energized 75 with (+) energy from contact 14 of lever SML

which again picks up relays W and WZ, after which relay WK is again energized over X line and its stick circuit again established as normally indicated.

75 *Signal control.*—It will now be assumed that the operator desires to allow a train movement from the main track to the right onto the diverging track over the track switch in its reverse position. The signal control lever SGL is moved in its east (right) position which closes a circuit for energizing the Y line with (+) energy extending from (+), contact 19 of lever SGL in its right hand dotted position, front contact 28 of relay WK, winding of relay G, Y line conductor, winding of relay GZ, contact 121 of relay WZ in its left hand dotted position, contact 122 of relay WP in its left hand dotted position, front contact 123 of relay WP and front contact 124 of relay T to (C).
 10

15 Relays G and GZ are energized by the current flow over Y line and relay G opens the circuit of relay OSR at back contact 21 before OSR has time to close its contact 24. The polar contact of relay GZ is actuated to the right which closes a circuit for clearing signal ES extending from 25 (+), front contact 100 of relay GZ, contact 102 of relay GZ in its right hand position and through the various auxiliary circuits (not shown) to signal ES.
 20

25 In response to the clearing of signal ES, relay 30 EM is de-energized which closes a circuit for energizing W line with (—) energy which extends from (C), winding of relay GK, front contact 18 of relay G, W line conductor front contact 116 of relay GZ and back contact 125 35 of relay EM to (+). This (—) energization of W line picks up the neutral contact of relay GK and positions its polar contact to the right. A circuit is now closed for lighting lamp ESK as an indication that signal ES is clear, which circuit extends from (+), front contact 13 of relay GK, contact 23 of relay GK in its right hand position and lamp ESK to (—).
 40

45 It is believed that the manner in which a signal may be cleared for traffic to the left over track switch TS is obvious from the foregoing description. However it will be briefly pointed out that the operation of lever SGL to the left applies (—) energy by way of contact 19 in its left hand dotted position over the above described circuit 50 including Y line conductor. Current flowing over this circuit picks up relay G, energizes relay GZ and positions its polar contacts to the left, whereby a circuit is closed through contact 102 in its left hand dotted position to clear signal WS 55 or WSA in accordance with the track switch is in its normal or reverse position respectively.
 55

60 *Track occupancy.*—Having described the manner in which the track switch is controlled from the control office and the signals are governed 60 for traffic over this switch, it will now be assumed that a train enters the illustrated track section with which the illustrated track switch is associated, thereby dropping relay T.
 65

The opening of front contact 124 of relay T 65 de-energizes the above described signal control circuit including Y line wire which is effective to de-energize relays G and GZ. The opening of contact 100 of relay GZ de-energizes the circuit leading to signal ES which puts this signal to 70 stop.
 70

The dropping of relay G de-energizes relay GK at open front contact 16, which causes front contact 13 to open and de-energize lamp ESK as an indication that the corresponding signal at the 75

station is at stop. The de-energization of the circuit leading to lamp ES at the station causes relay EM to pick up and open the above described circuit including W line conductor.

- 5 A circuit is now closed for picking up relay OSR which extends from (+), contact 19 of lever SGL in its right hand dotted position, front contact 20 of relay WK, back contact 21 of relay G and winding of relay OSR to (C). The picking up of 10 relay OSR extends this circuit from (+) by way of its front contact 24 and back contact 22 of relay W to lamp OS for lighting this lamp as an indication that the associated track section is occupied. It will be obvious that the circuit 15 from contact 19 of lever SGL is not completed through the winding of relay G at this time because of open front contact 124 of relay T.

Track unoccupancy.—As soon as the train leaves the track section, relay T is picked up to 20 energize Y line conductor with (+) energy over the above described circuit and relay G is picked up. The opening of back contact 21 of relay G de-energizes and drops relay OSR which opens its 25 front contact 24 for de-energizing lamp OS as an indication that the associated track section is unoccupied.

Relays G and GZ are energized in response to the re-energization of Y line conductor and the closure of front contact 100 of relay GZ again 30 clears signal ES in the event that the signal lever at the office has not yet been restored to its stop position. Relay EM is dropped in response to the clearing of signal ES and (—) energy is again applied to W line conductor over the circuit previously described which includes back contact 125 of relay EM.

In response to the (—) energization of W line conductor, relay GK is again energized to display signal ESK over the previously described circuit 40 as an indication that the associated signal ES at the station is clear.

When the operator restores lever SGL to its stop position, Y line conductor is de-energized at open contact 19 which effects the de-energization 45 of relays G and GZ. The dropping of relay GZ de-energizes the circuit to signal ES for putting this signal to stop, after which relay EM is again picked up.

The dropping of relay G de-energizes the W 50 line circuit including relay GK, which effects the release of this relay for de-energizing lamp ESK.

Approach section 1A occupied.—The present circuit arrangement provides means for energizing X line with (+) energy in response to the 55 occupancy of section 1A at the illustrated field station. The occupancy of section 1A causes relay T¹ to be de-energized which closes a circuit for energizing X line with (+) energy, which circuit extends from (+), back contact 110 60 of relay TPX, front contact 111 of relay T², back contact 112 of relay T¹, back contact 117 of relay WZ, X line conductor, back contact 17 of relay W, rectifier 1R and upper winding of relay 65 1TK to (C). Relay 1TK picks up and closes a circuit at its front contact 25 for lighting lamp 1AT as an indication that track section 1A is occupied.

When section 1A becomes unoccupied, relay 70 T¹ is picked up and the above described energizing circuit for X line conductor is interrupted at open back contact 112. This de-energizes relay 1TK in the control office which in turn puts out the indicating lamp 1AT.

In the event that track section 2A is occupied, 75 relay T² is de-energized and X line conductor

is energized with (—) energy over a circuit extending from (—), back contact 113 of relay TPX, back contact 114 of relay T², back contact 117 of relay WZ, X line conductor back contact 17 of relay W, rectifier 2R and upper winding 5 of relay 2TK to (C).

Relay 2TK is picked up and a circuit is closed at its front contact 26 for lighting lamp 2AT as an indication that the associated track section 2A is occupied. When relay T² picks up in response to the unoccupancy of section 2A, the above described energizing circuit for X line is interrupted at open back contact 114 which releases relay 2TK for putting out lamp 2AT.

In order to indicate both track circuits 1A 15 and 2A over the same X line circuit relays T¹ and T² control the energization of the indicating relays 1TK and 2TK by opposite polarity, with rectifiers being used to render these relays responsive to polarity. The above description 20 points out how indications are transmitted in response to the occupancy of both track sections one at a time and it will now be explained how the occupancy and unoccupancy of these track sections in various sequences effect the control 25 of relays 1TK and 2TK for giving the proper indications.

It will first be assumed that both track sections 1A and 2A become occupied at the same time. When relay T² is dropped in response to the occupancy of section 2A (—) energy is applied over the above described circuit including X line and back contacts 113 and 114 of relays TPX and T² respectively. Inasmuch as relays T¹ and T² drop away together, front contact 111 is opened before back contact 112 closes, so that there is no (+) applied to the X line until after the application of (—) energy. The simultaneous dropping of relays T¹ and T² completes a pick-up circuit for relay TPX through back contacts 126 40 and 127 of relays T¹ and T² respectively and back contact 128 of relay WZ. Since relay TPX is slow to pick up, the above described circuit for energizing X line with (—) energy is completed for a substantial period of time before 45 relay TPX picks up and opens back contact 113. When relay TPX picks up, because both relays T¹ and T² are de-energized, the (—) energy is cut off of X line and (+) energy is at once applied. The (—) energy applied to X line 50 is effective to pick up relay 2TK and the (+) energy applied to X line is effective to pick up relay 1TK as above described. Relay 2TK is slightly slow to release so that the picking up of relay 1TK closes a stick circuit for relay 2TK 55 before it releases, which extends from (+), front contact 27 of relay 1TK, front contact 28 of relay 2TK and lower winding of relay 2TK to (—). It is obvious that with relays 1TK and 2TK both 60 picked up the above described circuits for lighting lamps 1AT and 2AT are complete which gives an indication that both track sections 1A and 2A are occupied.

In the event that track section 2A is occupied when a train enters section 1A, relay T² will be 65 down and then when relay T¹ drops, the (—) energy applied through back contact 114 of relay T² for energizing relay 2TK is maintained until relay TPX opens its back contact 113 to apply (+) energy, by way of its front contact 110 and back contacts 111 and 112 of relays T² and T¹ respectively, to the X line for picking up relay 1TK, after which relay 2TK is stuck up as before.

It will now be assumed that both sections 1A and 2A are occupied and that the train leaves 75

section 1A first. The picking up of relay T¹ opens the circuit leading to (+) at back contact 112, which is effective to cause the release of both relays 1TK and 2TK in the office before relay 5 TPX at the station drops. When relay TPX drops, (—) is applied to the X line conductor through back contacts 113 and 114 of relays TPX and T² respectively, which causes relay 2TK to pick up and close the circuit for lighting lamp 2AT.

10 In the event that relay T² picks up first because the train leaves track section 2A first, then current is cut off of the X line at back contact 111 until relay TPX drops, after which (+) is applied to the X line by way of back contact 110, 15 front contact 111 and back contact 112 for picking up relay 1TK over the above described circuit and this relay in turn lights lamp 1AT.

It will be obvious that these approach indications are transmitted over the X line while relays 20 W and WZ are de-energized, that is when no switch controls or indications are being transmitted. In the event that the switch lever is shifted while an approach indication is displayed, the picking up of relay W closes obvious stick circuits 25 at its front contacts 29 and 30 for relays 2TK and 1TK respectively. The picking up of relay WZ opens the pick-up circuit of relay TPX at back contact 128 so that if there is a change in the occupancy of the approach track circuits 30 during the time the transmission of approach indications is interrupted, such change will be registered when W and WZ are again dropped.

It is to be understood that, although one specific embodiment of the invention has been disclosed, the principles set forth may be applied to various other types of systems and various complicated track layouts may be controlled in a similar manner, the present disclosure being chosen merely for the sake of simplicity and 40 clearness in describing the invention.

Having described a traffic controlling system as one specific embodiment of the present invention, it is desired to be understood that this form is selected to facilitate in the disclosure of the invention rather than to limit the number of forms which it may assume and it is further to be understood that various modifications, adaptations and alterations may be applied to the specific form shown to meet the requirements of practice, without in any manner departing from the 45 spirit or scope of the present invention except as limited by the appended claims.

Having described my invention, what I claim is:—

55 1. In a centralized traffic controlling system for railroads, a control office and a field station connected by a plurality of line wires, a switch control lever and a signal control lever at said office, a track switch and associated signals at 60 said station, means controlled by the operation of said switch control lever for energizing a first line circuit including one of said line wires, means responsive to the energization of said first line circuit for controlling the operation of said track switch, means controlled by the operation of said signal control lever for energizing a second line circuit including another of said line wires, means 65 responsive to the energization of said second line circuit for controlling the operation of said signals, means responsive to the energization of said second line circuit for transferring said one line wire from said first line circuit to a third line circuit, means for transmitting indications of the 70 conditions of said signals over said third line circuit, means for transmitting OS indications over 75 said second line circuit, a stick relay having a stick circuit including a visual OS indicator, and a pick-up circuit for said stick relay controlled over said second line circuit by the transmitted OS indications.

5 said second line circuit, a stick relay having a stick circuit including a visual OS indicator, and a pick-up circuit for said stick relay controlled over said second line circuit by the transmitted OS indications.

2. In a centralized traffic controlling system for railroads, a control office and a field station connected by a plurality of line wires, a switch control lever and a signal control lever at said office, a track switch and associated signals at 10 said station, means controlled by the operation of said switch control lever for energizing a first line circuit including one of said line wires, means responsive to the energization of said first line circuit for controlling the operation of said track switch, means controlled by the operation of said signal control lever for energizing a second line circuit including another of said line wires, means responsive to the energization of said second line circuit for controlling the operation of said signals, means responsive to the energization of said second line circuit for transferring said one line wire from said first line circuit to a third line circuit, means for transmitting indications of the 15 conditions of said signals over said third line circuit, means for transmitting OS indications over said second line circuit, and means for transmitting indications of said switch positions over a fourth line circuit including a third one of said line wires.

20 3. In a centralized traffic controlling system for railroads, a control office and a field station connected by a plurality of line wires, a switch control lever and a signal control lever at said office, a track switch and associated signals at 25 said station, means controlled by the operation of said switch control lever for characteristically energizing a first line circuit including one of said line wires, means responsive to the character of energization of said first line circuit for characteristically controlling the operation of said track switch, means controlled by the operation of said signal control lever for characteristically energizing a second line circuit including another of said line wires, means responsive to the character of energization of said second line circuit for characteristically controlling the operation of said signals, means responsive to the energization of said second line circuit for transferring said one line wire from said first line circuit to a third line circuit, means for transmitting indications of the 30 conditions of said signals over said third line circuit, means for transmitting OS indications over said second line circuit, and means for transmitting indications of said switch positions over a fourth line circuit including a third one of said line wires.

35 4. In a centralized traffic controlling system for railroads, a control office and a field station connected by a plurality of line wires, a switch control lever and a signal control lever at said office, a track section and associated track switch at said station, signals associated with said track switch, means controlled by the operation of said switch control lever for energizing a first line circuit including one of said line wires from a source of current at said office, means responsive to the energization of said first line circuit from said source of current at said office for controlling the operation of said track switch, means controlled by the operation of said signal control lever for energizing a second line circuit including another of said line wires from said source of current at said office, means responsive to the energization of said second line circuit from said 40 source of current at said office for controlling the operation of said track switch, means controlled by the operation of said signal control lever for energizing a second line circuit including another of said line wires from said source of current at said office, means responsive to the energization of said second line circuit from said 45 source of current at said office for controlling the operation of said track switch, means controlled by the operation of said signal control lever for energizing a second line circuit including another of said line wires from said source of current at said office, means responsive to the energization of said second line circuit from said 50 source of current at said office for controlling the operation of said track switch, means controlled by the operation of said signal control lever for energizing a second line circuit including another of said line wires from said source of current at said office, means responsive to the energization of said second line circuit from said 55 source of current at said office for controlling the operation of said track switch, means controlled by the operation of said signal control lever for energizing a second line circuit including another of said line wires from said source of current at said office, means responsive to the energization of said second line circuit from said 60 source of current at said office for controlling the operation of said track switch, means controlled by the operation of said signal control lever for energizing a second line circuit including another of said line wires from said source of current at said office, means responsive to the energization of said second line circuit from said 65 source of current at said office for controlling the operation of said track switch, means controlled by the operation of said signal control lever for energizing a second line circuit including another of said line wires from said source of current at said office, means responsive to the energization of said second line circuit from said 70 source of current at said office for controlling the operation of said track switch, means controlled by the operation of said signal control lever for energizing a second line circuit including another of said line wires from said source of current at said office, means responsive to the energization of said second line circuit from said 75 source of current at said office for controlling the operation of said track switch.

source of current at said office for controlling the operation of said signals, means including a relay at the control office and another relay at the field station both responsive to the energization of 5 said second line circuit for transferring said one line wire from said first line circuit to a third line circuit, means for transmitting indications of the condition of said signals over said third line circuit by energy from a source of current at said 10 station, means for transmitting OS indications over said second line circuit by energy from said source at said control office, a stick relay, a pick-up circuit for said stick relay controlled over said second line circuit in accordance with the OS 15 indications transmitted, and a stick circuit for said stick relay controlled by the condition of energization of said first line circuit.

5. In a centralized traffic controlling system for railroads, a control office and a field station connected by a plurality of line wires, a switch control lever and a signal control lever at said office, a track section and associated track switch at said station, signals associated with said track switch, means controlled by the operation of said 20 switch control lever for energizing a first line circuit including one of said line wires from a first source of current at said office, means responsive to the energization of said first line circuit from said first source of current for controlling the 25 operation of said track switch, means controlled by the operation of said signal control lever for energizing a second line circuit including another of said line wires from said first source of current, means responsive to the energization of said 30 second line circuit from said first source of current for controlling the operation of said signals, means responsive to the energization of said second line circuit for transferring said one line wire from said first line circuit to a third line 35 circuit, means for transmitting indications of the condition of said signals over said third line circuit from a second source of current at said station, means for transmitting indications of the condition of said signals over said second line circuit from said first source of current for preparing said fourth line circuit for the transmission of switch indications, and means for transmitting indications of the position of said 40 track switch over said fourth line circuit.

6. In a centralized traffic controlling system for railroads, a control office and a field station connected by a plurality of line wires, a switch control lever and a signal control lever at said office, a track section and associated track switch at said station, signals associated with said track switch, means controlled by the operation of said switch 45 control lever for energizing a first line circuit including one of said line wires from a first source of current at said office, a switch control relay responsive to the energization of said first line circuit from said first source of current for controlling the operation of said track switch, means controlled by the operation of said signal control lever for energizing a second line circuit including another of said line wires from said first source of current, means responsive to the energization of said 50 second line circuit from said first source of current for controlling the operation of said signals, means responsive to the energization of said second line circuit for transferring said one line wire from said first line circuit to a third line circuit, means for transmitting indications of the 55 condition of said signals over said third line circuit from a second source of current at said station, and means for transmitting indications of said approach sections over a fourth line circuit including a third one of said line wires.

7. In a centralized traffic controlling system for railroads, a control office and a field station connected by a plurality of line wires, a switch control lever and a signal control lever at said office, a track section and associated track switch at said station, an approach track section, signals associated with said track switch, means controlled by the operation of said switch control lever for energizing a first line circuit including one of said line wires from a first source of current at said office, means responsive to the energization of said first line circuit from said first source of current for preparing said fourth line circuit for the transmission of switch indications, and means for transmitting indications of the position of said track switch over said fourth line circuit only when said switch control relay and said track switch are in corresponding positions.

8. In a centralized traffic controlling system for railroads, a control office and a field station connected by a plurality of line wires, a switch control lever and a signal control lever at said office, a track section and associated track switch at said station, a plurality of approach track sections, signals associated with said track switch, means controlled by the operation of said switch control lever for energizing a first line circuit including one of said line wires from a first source of current at said office, means responsive to the energization of said first line circuit from said first source of current for controlling the operation of said track switch, means controlled by the operation of said signal control lever for energizing a second line circuit including another of said line wires from said first source of current, means responsive to the energization of said second line circuit from said first source of current for controlling the operation of said signals, means responsive to the energization of said second line circuit for transferring said one line wire from said first line circuit to a third line circuit, means for transmitting indications of the conditions of said signals over said third line circuit from a second source of current at said station, means for transmitting OS indications for said track section over said second line circuit from said first source of current, and means for transmitting approach indications of said approach section over a fourth line circuit including a third one of said line wires.

9. In a centralized traffic controlling system for railroads, a control office and a field station connected by a plurality of line wires, a switch control lever and a signal control lever at said office, a track section and associated track switch at said station, a plurality of approach track sections, signals associated with said track switch, means controlled by the operation of said switch control lever for energizing a first line circuit including one of said line wires from a first source of current at said office, means responsive to the energization of said first line circuit from said first source of current for controlling the operation of said track switch, means controlled by the operation of said signal control lever for energizing a second line circuit including another of said line wires from said first source of current, means responsive to the energization of said second line circuit from said first source of current for controlling the operation of said signals, means responsive to the energization of said second line circuit for transferring said one line wire from said first line circuit to a third line circuit, means for transmitting indications of the conditions of said signals over said third line circuit from a second source of current at said station, and means for transmitting indications of said approach sections over a fourth line circuit including a third one of said line wires.

10. In a centralized traffic controlling system for railroads, a control office and a field station connected by a plurality of line wires, a switch control lever and a signal control lever at said office, a track section and associated track switch at said station, a plurality of approach track sections, signals associated with said track switch, means controlled by the operation of said switch control lever for energizing a first line circuit including one of said line wires from a first source of current at said office, means responsive to the energization of said first line circuit from said first source of current for preparing said fourth line circuit for the transmission of switch indications, and means for transmitting indications of the position of said track switch over said fourth line circuit only when said switch control relay and said track switch are in corresponding positions.

5 railroads, a control office and a field station connected by a plurality of line wires, a switch control lever and a signal control lever at said office, a track section and associated track switch at said station, a plurality of approach track sections, signals associated with said track switch, means controlled by the operation of said switch control lever for energizing a first line circuit including one of said line wires from a first source of current at said office, means responsive to the energization of said first line circuit from said first source of current for controlling the operation of said track switch, means controlled by the operation of said signal control lever for energizing a second line circuit including another of said line wires from said first source of current, means responsive to the energization of said second line circuit for transferring said one line wire from said first line circuit to a third line circuit, means for transmitting indications of the conditions of said signals over said third line circuit from a second source of current at said station, means for transmitting indications of said approach sections over a fourth line circuit including a third one of said line wires, and means for preventing the transmission of said approach indications when said first line circuit is energized from said first source of current.

10. In a centralized traffic controlling system for railroads, a control office and a field station connected by a plurality of line circuits, means including a switch control lever for distinctively controlling a track switch at said station by distinctively energizing a first one of said line circuits at said office, normal and reverse switch position indicating signals in said office, a switch position indicating relay in said office, means for distinctively energizing said relay from energy applied to a second one of said line circuits at said station in accordance with the position of said track switch, and circuit means both for sticking said relay and energizing the proper normal or reverse switch position indicating signal over circuits selected by said relay and said lever.

11. In a centralized traffic controlling system for railroads, a control office and a field station connected by a first and a second line circuit, a switch control lever at said office arranged to control the operation of a track switch at said station over said first line circuit, a switch position indicating relay at said office, a stick circuit for said switch position indicating relay arranged to be deenergized by a change in position of said lever, a pick-up circuit for said switch position indicating relay including said second line circuit and momentarily energized in accordance with the operated position of said track switch only when said track switch and said lever are in correspondence, means for energizing said stick circuit only when said lever and said switch position indicating relay are in correspondence, and switch position and correspondence visual indicating means energized over said stick circuit.

12. In combination, a control lever and a track switch connected by a first line circuit including one line wire, a switch position indicating relay associated with said lever and connected to a switch position indicator associated with said track switch by a second line circuit including another line wire, means for transmitting switch controls from said lever to said track switch over said first line circuit, means for transmitting

switch position indications from said indicator to said switch position indicating relay over said second line circuit, a plurality of insulated track sections associated with said track switch, a plurality of track occupancy indicating relays associated with said control lever, a rectifier means, and means for transmitting track occupancy indications from said track sections to said track occupancy indicating relays over a third line circuit including said another line wire by way of said rectifier means.

13. In combination, a control lever and a track switch connected by a first line circuit including one line wire, a switch position indicating relay associated with said lever and connected to a switch position indicator associated with said track switch by a second line circuit including another line wire, means for transmitting switch controls from said lever to said track switch over said first line circuit, means for transmitting switch position indications from said indicator to said switch position indicating relay over said second line circuit, a plurality of insulated track sections associated with said track switch, a plurality of track occupancy indicating relays associated with said control lever, a rectifier means, means for transmitting track occupancy indications from said track sections to said track occupancy indicating relays over a third line circuit by way of said rectifier and said another line wire, signals associated with said track switch, signal indicators associated with said lever, and means for transmitting signal indications from said signals to said signal indicators over a fourth line circuit including said one line wire.

14. In combination, a control lever and a track switch connected by a first line circuit including one line wire, a switch position indicating relay associated with said lever and connected to a switch position indicator associated with said track switch by a second line circuit including another line wire, means for transmitting switch controls from said lever to said track switch over said first line circuit, means for transmitting switch position indications from said indicator to said switch position indicating relay over said second line circuit, a plurality of insulated track sections associated with said track switch, a plurality of track occupancy indicating relays associated with said control lever, a rectifier means, means for transmitting track occupancy indications from said track sections to said track occupancy indicating relays over a third line circuit including said another line wire by way of said rectifier, signals associated with said track switch, signal indicators associated with said lever, means for transmitting signal indications from said signals to said signal indicators over a fourth line circuit including said one line wire, and means for transferring said one line wire from switch control to signal indication transmission and said another line wire from switch position indication to track occupancy indication transmission.

15. In combination; a switch machine for operating a track switch; a control lever having two extreme positions for governing the operation of said switch machine to either of two extreme positions; indication means for indicating the position of said switch machine and the track switch; a polar neutral stick relay; a pick-up circuit for said stick relay closed only when and only momentarily each time said control lever and said indication means are operated into corresponding positions; stick circuit means for said stick relay including its own winding, its own

- neutral front contact and a contact on said control lever closed only when said lever and the polar contacts of said stick relay are in corresponding positions; and a plurality of indicators selectively energized over said stick circuit means whereby a distinctive indication is displayed each time said control lever, said switch machine and the track switch are operated into corresponding positions and the displayed indication is annulled each time said control lever is moved to a new position.
16. In combination; a railway track switch; a plurality of signals for governing the movement of traffic over the switch; switch and signal control relays adjacent the switch; a first wire, a second wire, a third wire and a common return wire extending from the switch to a remote point; switch and signal indication relays and electro-responsive selector means at said remote point; means for energizing the switch control and switch indication relays over said first and said second wires respectively and said common return wire when the electro-responsive means is deenergized; means for energizing the signal control relay and the electro-responsive means over said third wire and said common return wire; and means for energizing the signal indication relay over said first wire and said common return wire when the electro-responsive means is energized.
17. In a centralized traffic controlling system for railroads, a control office and a field station connected by a first and a second line wire, control means including a switch control lever at said office arranged to control the operation of a track switch at said station over a first line circuit including said first line wire, a switch position indicating relay at said office, a pick-up circuit for said switch position indicating relay including said second line wire and momentarily energized in accordance with the operated posi-

tion of said track switch only when said track switch and said control means are in correspondence, a stick circuit for said switch position indicating relay energized only when said lever and said switch position indicating relay are in correspondence, switch position and correspondence visual indicating means energized over said stick circuit, means for at times switching said second line wire from said switch position indicating relay to a circuit portion including a traffic condition receiving device, and means for energizing said circuit portion in accordance with traffic conditions at said station.

18. In a centralized traffic controlling system for railroads, a power operated track switch, switch control means including a control lever for governing the power operation of said track switch, a relay which must be deenergized to allow said control lever to govern said track switch, a pick-up circuit for said relay energized only when said track switch is in correspondence with said switch control means and only when said lever is capable of controlling said track switch, and stick circuit means for said relay deenergized by movement of said lever.

19. In a centralized traffic controlling system for railroads, a power operated track switch, switch control means including a lever for governing the power operation of said track switch, a polar-neutral relay which indicates the normal or reverse position of said track switch, a pick-up circuit for said relay energized with one polarity or the other momentarily each time and only when said track switch operates into correspondence with the normal or reverse position of said control means, and stick circuit means for said relay energized only when said lever is in a normal or reverse position corresponding to the normal or reverse position indicated by said relay.
